FIRING CIRCUIT FOR IGNITRONS

William E. Pakala, Forest Hills, Pa., assignor to
Westinghouse Electric Corporation, East Pittsburgh, Pa., a corporation of Pennsylvania

Application July 19, 1940, Serial No. 346,287

4 Claims. (Cl. 315—141)

My invention relates to vapor electric converters and particularly to a control system for controlling the instant of ignition of a make-alive type valve.

In the operation of vapor electric devices such as make-alive type valves considerable difficulty has been experienced in securing proper application of the control potentials to the make-alive electrode for initiating the conducting cycle in the valve. Heretofore it has been customary to use mechanical contact devices or auxiliary electric valves for applying the make-alive potential to the make-alive electrode. It has also been proposed to utilize so-called peaked wave generators for applying potential to the make-alive electrodes. These prior devices have had certain disadvantages in that the auxiliary valves were of short life and consequently required replacing at frequent intervals. Contact devices were also unsatisfactory in that the contact points were readily burned or destroyed in operation.

I have found that satisfactory operation can be secured by utilizing a normal alternating current control source and distorting the wave form by means of suitable saturable reactors to produce a so-called peak wave for applying to the make-alive electrode.

It is therefore an object of my invention to provide a control system utilizing saturable reactors to control the application of a peaked impulse to the make-alive electrode.

It is a further object of my invention to provide a cheap and reliable control device for a vapor electric device.

Other objects and advantages of my invention will be apparent from the following detailed description taken in conjunction with the accompanying drawings in which:

Figure 1 is a schematic illustration of a vapor electric converter according to my invention;

Fig. 2 is a diagrammatic illustration of the wave form as secured by my improved impulsive device, and

Fig. 3 is a modification according to my invention.

In an exemplary embodiment of my invention according to Fig. 1, an alternating current circuit 1 is connected to a direct current circuit 2 by means of a suitable rectifier transformer 3, the flow of current through the transformer being regulated by means of the vapor electric converter composed of a plurality of make-alive type valves 4. Each valve 4 includes a vaporizable cathode 5 of suitable material such as mer-

cury, a cooperating anode 6, a suitable shield 7 enclosing the anode 6 and a make-alive electrode 8 in contact with or partially immersed in the cathode 5.

5 The control system according to my invention comprises a suitable alternating-current source shown in the form of a control transformer 9 having a plurality of secondary phase windings 10 corresponding in number to the make-alive electrodes 8 to be controlled. The primary 11 of the control transformer 9 is connected in any suitable alternating current source such as the alternating current circuit 1. Preferably a phase shifting device such as the induction phase shifter 12 is inserted between the alternating current source 1 and the primary 11 of the control transformer 9.

20 As the control transformer 9 produces a substantially sinusoidal wave shape, and as a steeply rising or peaked wave shape is desirable for application to the make-alive electrode, I have introduced a saturable reactor 13 which includes a winding 14 in series between the phase terminals 15 of the control transformer 9 and the associated make-alive electrodes 8. Each series winding 14 is associated with a magnetic core 16 of a material having high permeability and a sharp saturation point. Preferably a suitable unidirectional conductor or asymmetrically conducting device 17 or rectifying device is inserted in series with the make-alive electrode 8 so that the control impulses of only the desired polarity are conducted to the make-alive electrode 8. In order to block out the inverse potential from the 25 make-alive electrode 8, while still permitting the flow of the inverse current-impulses in the reactor-winding 14 and in the transformer-winding 10, producing therein a symmetrical alternating current without any direct-current component in 30 said reactor-winding 14 or said transformer-winding 10, a suitable unidirectional conductor or asymmetrically conducting device 18 is usually inserted in shunt with the make-alive electrode 8 and the first-mentioned series rectifier 17.

35 In the operation of the device according to my invention, the control transformer 9 produces a substantially sinusoidal control wave of equal positive and negative half-waves, which is impressed on the winding 14 of the saturable reactor 13. The dimensions of the reactor 13 are so chosen, with reference to the magnitude of the impressed sinusoidal voltage-wave, that as soon as current in the saturable reactor 13 rises to a predetermined point in each of the positive and negative impulses or half-waves, said

current will be sufficient to saturate the core 16 of the reactor, whereby a discontinuity in the saturation-curve of the reactor is obtained at said portion of each positive and negative impulse, and a rapid increase in current takes place to produce a strongly peaked wave form 20 as diagrammatically illustrated in Fig. 2.

The series rectifier 17 permits the passage of a half-wave of this potential 20 to the make-alive electrode 8 while the shunt rectifier 18 shunts out the inverse half-cycle so that during the forward half-cycle a cathode spot will be formed in the valve 4 by the flow of potential through the series rectifier 17 and the make-alive electrode 8 and during the inverse half cycle 15 there will be no action at the make-alive electrode 8.

In order to permit ready pick up of the main arc from the anode 6, the shield 7 is connected to a suitable source of in-phase potential herein 20 illustrated as the anode circuit. After the formation of the cathode spot a preliminary discharge will take place from the anode shield 7 thus ionizing the anode space and permitting the ready pick up of the current carrying arc 25 to the anode 6.

In the modification of my invention according to Fig. 3 suitable capacitors 21 have been connected in series with the winding 14 of the saturable reactors 13 to produce a steeper impulse of shorter duration than is secured by means of the saturable reactor 13 alone. A steep wave-front of the impressed voltage-wave sending current through the reactor 13 and the make-alive electrode 8 is particularly useful, in the make-alive control of the rectifier-valves 4, because the condition of the make-alive electrode changes, from time to time, thus causing the magnetizing current of the serially connected reactor 13 to vary. If the wave-fronts of the successive half-cycles of this magnetizing-current are steep, the point at which saturation occurs will occur at very nearly the same time-phase in each half-cycle, regardless of the condition of the make-alive electrode, thus making the operation of the vapor-electric valves 4 more uniform anode shields 7 have been connected to a source controllable in phase with relation to the potential applied to the main anode. While any suitable source of control potential can be utilized, I prefer to use an intermediate tap 22 on each of the phase windings 10 of the control transformer 9 to secure a suitable potential for application to the anode shield 7.

While for purposes of illustration I have shown and described specific embodiments of my invention, it will be apparent that changes and modifications can be made therein without departing from the true spirit of my invention or the scope of the appended claims.

I claim as my invention:

1. A make-alive control-system comprising a vapor-electric valve-device; an alternating-current source; a saturable reactor; a series asymmetrically conducting device; a shunting asymmetrically conducting device; a make-alive circuit including, in series-circuit relation, said alternating-current source, said saturable reactor, said series asymmetrically conducting device, and a make-alive electrode of said valve-device, whereby unidirectional-current impulses of one polarity are delivered, through said series asymmetrically conducting device, to said make-alive electrode; and a shunting circuit, including said shunting asymmetrically conducting device, con-

nected in shunt-circuit relation around said make-alive electrode and said series asymmetrically conducting device, whereby a path is provided for unidirectional-current impulses of the other polarity; said alternating-current source and said reactor adapted to carry substantially symmetrical current-impulses, with the currents in opposite directions substantially equal to each other.

2. A make-alive control-system comprising a vapor-electric valve-device, an alternating-current source; an inductance-device having a saturable core; a series asymmetrically conducting device; a shunting asymmetrically conducting device; circuit-means, including said alternating-current source, for impressing upon said inductance-device an alternating voltage having substantially equal positive and negative impulses, said impulses having sufficient magnitude to saturate the inductance-device at a portion of each of the positive and negative impulses, whereby a discontinuity in the saturation-curve of the inductance-device is obtained at said portion of each positive and negative impulse; make-alive circuit-means, including said series asymmetrically conducting device, for utilizing said inductance-device to cause peaked positive current-impulses to be supplied to a make-alive electrode of said valve-device; and a shunting circuit, including said shunting asymmetrically conducting device, connected in shunt-circuit relation around said make-alive electrode and said series asymmetrically conducting device, whereby a path is provided for the peaked negative current-impulses.

3. A control system comprising, an alternating-current source; an inductance-device having a saturable core; a series asymmetrically conducting device; a shunting asymmetrically conducting device; circuit-means, including said alternating-current source, for impressing upon said inductance-device an alternating voltage having substantially equal positive and negative impulses, the magnitude of said impulses being sufficient to saturate the inductance-device at a portion of each of the positive and negative impulses, whereby a discontinuity in the saturation-curve of the inductance-device is obtained at said portion of each positive and negative impulse; a current-supplying circuit-means, including said series asymmetrically conducting device, for utilizing said inductance-device to cause peaked positive current impulses to be supplied to a load-device; and a shunting circuit, including said shunting asymmetrically conducting device, connected in shunt-circuit relation around said load device and said series asymmetrically conducting device, whereby a path is provided for the peaked negative current-impulses.

4. A control system comprising, an alternating-current source; an inductance-device having a saturable core; a capacitor; a series asymmetrically conducting device; a shunting asymmetrically conducting device; circuit-means, including said alternating-current source; and also including said capacitor and said inductance device, for impressing upon said inductance-device an alternating voltage having substantially equal positive and negative impulses, the magnitude of the impulses being sufficient to saturate the inductance-device at a portion of each of the positive and negative impulses, whereby a discontinuity in the saturation-curve of the inductance-device is obtained at said portion of each positive and negative impulse; said capaci-

tor and said inductance device being connected in series for controlling the shape and duration of the current impulses, a current-supplying circuit-means, including said series asymmetrically conducting device, for utilizing said inductance-device to cause peaked positive current-impulses to be supplied to a load-device; and a

shunting circuit, including said shunting asymmetrically conducting device, connected in shunt-circuit relation around said load device and said series asymmetrically conducting device, whereby a path is provided for the peaked negative current-impulses.

WILLIAM E. PAKALA.
